UNITED STATES PATENT OFFICE.

JACK H. LAMBERTON, OF SANTA MONICA, CALIFORNIA.

DESIGN FOR A SHIRT.

Application filed May 14, 1926. Serial No. 17,724. Term of patent 3½ years.

To all whom it may concern:

Be it known that I, JACK H. LAMBERTON, a citizen of the United States, residing at Santa Monica, in the county of Los Angeles and State of California, have invented a new, original, and ornamental Design for Shirts, of which the following is a specification, reference being had to the accompanying drawing, forming part thereof.

The figure is a perspective view of a shirt, showing my new design the same being illustrated on a figure indicated in dotted lines.

I claim:

The ornamental design for a shirt, as shown and described.

JACK H. LAMBERTON.
